Primary Examiner — John Windmuller*Assistant Examiner* — Steven J Czyz(74) *Attorney, Agent, or Firm* — Sterne, Kessler, Goldstein & Fox P.L.L.C.(57) **CLAIM**

The ornamental design for a key, as shown and described.

DESCRIPTION

FIG. 1 is a front perspective view of a key showing the claimed design;

FIG. 2 is a side perspective thereof;

FIG. 3 is a front view thereof;

FIG. 4 is a rear view thereof;

FIG. 5 is a bottom view thereof;

FIG. 6 is a top view thereof;

FIG. 7 is a left side view thereof; and,

FIG. 8 is a right side view thereof.

The broken lines in the figures show portions of the key that form no part of the claimed design.

1 Claim, 8 Drawing Sheets(56)
